UNITED STATES PATENT OFFICE

ROLAND R. FOULKE, OF PHILADELPHIA, PENNSYLVANIA

AUTOMATICALLY-OPERABLE RAILWAY SWITCH

Application filed April 4, 1929. Serial No. 352,381.

The object of the invention is to enable the automatic operation of railroad switches from the engine, car or train which is to be switched from one track to another. Another object of the invention is to make the manual operation of the switch difficult or impracticable.

A preferred embodiment of the invention is shown in the accompanying drawings, in which—

Fig. 1 is a diagram, in plan, of a main track, a siding, a switch and my switch operating contrivance.

Fig. 2 is a horizontal sectional view of one of the switch boxes and of the mechanism contained therein and operated thereby to operate the switch.

Fig. 3 is a vertical sectional view through the central part of a switch box.

Fig. 4 is an end view of a rail and a part of a car thereon, means thereon to operate the mechanism of Fig. 2, and an end view of one of the switch boxes.

The rails *a*, *a*, of the two main track sections, the rails *b*, *b*, of a siding track, and a switch *c* at the junction of the two tracks, are shown in diagram in Fig. 1. The switch itself may be of any known construction, its construction forming no part of my invention. All that is required is that the laterally movable rail sections of the switch shall be operable by any convenient means, such as by one arm of a bell crank lever *d*. The other arm of the bell crank lever *d* is attached to, and between the ends of, a long rod *e*, which extends in substantial parallelism with the tracks.

The rod *e* is pivotally connected, at and near each end thereof, with corresponding ends of two levers *f*, *f'*, pivotally supported between their ends. The other corresponding ends of levers *f* are pivotally connected respectively with two aligning rods *g*, *g'*, which extend through, and are longitudinally slidable in, the respective closed end heads of a tubular-shaped switch box *h*.

The box *h* has in its interior an annular central abutment *i* against opposite ends of which abut blocks *k*, *k'*, which are held respectively against abutment *i* by means of

coil springs *m*, *m'*, confined between the respective blocks *k*, *k'*, and the end heads of the box.

In either of the two positions of switch *c*, the inner end of one of the rods *g* or *g'* is relatively close to the corresponding block *k* or *k'*, while the inner end of the other rod is relatively distant from the corresponding block, so as to provide for the operations hereinafter described.

Projecting above box *h* are lugs *n*, *n*, between which is pivoted, on an axis extending transversely of the box, an operating lever *o*. The lower end of lever *o* extends into the box between blocks *k* and *k'*. The upper end of lever *o* is in line of travel of an actuator *p* (Fig. 4) which may be carried on any one of the cars *q*, or on the locomotive, of the train which is to be switched from one track to another. The actuator *p* may be a pivoted lever, which is movable into and out of operative position, as indicated in Fig. 4; or it may be any other contrivance which is adapted to be positioned, by one of the train crew, so as to cause it, in the movement of the train, to engage and operate lever *o*.

Assume that the described mechanism is in the position shown in Figs. 1 and 2, that actuator *p* on the moving car is in the dotted (operative) position shown in Fig. 4 and that the train is moving in the left-hand direction, Fig. 1, toward switch *c*. Before the engine (or if the train is backing, before the rear car) reaches switch *c*, actuator *p* engages operating lever *o* and swings its lower end to the right, Fig. 2. Thereby block *k* is moved to the right, thereby pushing rod *g* and the upper end of lever *f* to the right, Fig. 2, and pushing the lower end of lever *f* and rod *e* to the left, Figs. 1 and 2, thus moving the switch *c* into position to connect the rails *a*, *a*, of one section of the main track with the rails *b*, *b*, of the siding. At the same time lever *f'* is swung to push rod *g'* inward. This movement of rod *g* performs no function except to position it for operating the switch in a reverse direction.

So far as the construction has been described, it would be readily operable by hand, since rod *g*, being disconnected from block

k, would be freely movable without spring resistance. To render hand operation difficult, the following auxiliary mechanism is provided.

5 Rod *e* extends through a box *r*, which may be conveniently secured to box *h*. Pivotally carried on rod *e*, within box *r*, is a ratchet lever *s*, which is held, in the position shown, against a stop *v* on rod *r*, by means of a 10 spring *t*. Pivotally mounted between its ends in box *r* is a lever *x*, one free end of which extends in front of ratchet *s*, while the other end is confined between heads *y*, *y'*, supported on the ends of slideable rods *z*, *z'*. 15 Coil springs *w*, *w'*, are confined between these heads and opposite ends of the box, and normally hold lever *x* in a central position.

When rod *e* is moved to the left, Fig. 2, ratchet *s* engages lever *x* and swings its 20 lower end to the left, and its upper end to the right compressing spring *w*. In the described operation of lever *x* by ratchet *s*, the latter rides under and beyond lever *x* and snaps back into its normal position. In the 25 return movement of rod *e*, ratchet *s* rides under the lower end of lever *x* and then is again snapped back into normal position by its spring *t*.

This auxiliary mechanism plays no part 30 in the operation of the switch except to make it difficult to operate by hand, since hand operation requires the compression of one of the springs *w*, which may be made too stiff and strong for practicable manual operation.

When the train, traveling in the reverse direction, moves from track *b*, *b*, to track *a*, *a*, the switch operating mechanism may be operated in the reverse direction to re-connect the rails *a*, *a*, of the two sections of the 40 main track. For this purpose, another actuator *p* should be secured to a car on the rear of the train, or on the locomotive, tender or first car if the train is moving backward, so that the switch will be operated after the entire train has returned to the 45 main track.

If, after the entire train has passed from track *a* to track *b*, it is desired, as it usually 50 will be, to operate the switch and re-connect the rails of the main track, other switch operating mechanism, which may be a duplicate of that described, may be operated to move rod *e* to the right, Fig. 1. This duplicate switch operating mechanism is indicated at *j*, Fig. 1. So, also, when it is thereafter desired to again connect the siding and the main track prior to returning the train 55 from the siding to the main track, switch operating mechanism *j* may be operated to move rod *e* to the left, Fig. 1.

Whenever either switch operating mechanism is operated to move the switch in one direction, it operates itself, and also the 60 other switch operating mechanism, to so po-

sition each switch operating mechanism that it is operable, by a train-carried actuator, to move the switch in the reverse direction.

Having now fully described my invention, what I claim and desire to protect by Letters Patent is:

1. The combination with two sections of a track, a second track which diverges from said track, and a switch movable into position to connect the rails of one of said track sections either with the rails of the other track section or with the rails of the other track, of a rod extending lengthwise of the tracks and operably connected with said switch, a lever adjacent one of said tracks, a spring-actuable member normally holding said lever in operable position and movable, against spring tension, by said lever, connections to said rod which are disconnected from, but operable by, said member, when so operated by said lever, to move said rod to operate the switch, and an actuator adapted to be carried by a moving train and operate said lever.

2. The combination with two sections of a track, a second track which diverges from said track, and a switch movable into position to connect the rails of one of said track sections either with the rails of the other track section or with the rails of the other track, of a rod extending lengthwise of the tracks and operably connected with said switch, a lever adjacent one of said tracks, spring-actuable members pressing in opposite directions against said lever and normally holding it 95 in a central position, said lever being forcibly movable in either direction to move either of said members against spring tension, connections to said rod which are operable, by each of said members, to move said rod in one direction or the other and thereby operate the switch in one direction or the other, and an actuator adapted to be carried by a moving train and operate said lever in one direction or the other dependent on the direction of travel of the train.

3. The combination with two sections of a track, a second track which diverges from said track, and a switch movable into position to connect the rails of one of said track sections either with the rails of the other track section or with the rails of the other track, of a rod extending lengthwise of the tracks and operably connected with said switch, a lever adjacent one of said tracks, a spring-actuable member normally holding said lever in operable position and movable, against spring tension, by said lever, connections to said rod which are disconnected from, but operable by, said member, when so operated by said lever, to move said rod to operate the switch, an actuator adapted to be carried by a moving train and operate said lever, and auxiliary mechanism adapted to resist said movement of the rod but permit said 130

movement when such connections are operated with a predetermined force.

4. The combination with two sections of a track, a second track which diverges from said track, and a switch movable into position to connect the rails of one of said track sections either with the rails of the other track section or with the rails of the other track, of a rod extending along one of said tracks and operatively connected with said switch, mechanism positioned alongside said track and operatively connected with said rod, and an actuator adapted to be carried by a moving train and adapted, dependent upon its direction, to operate said mechanism to move the rod in either direction, said mechanism comprising connections, operable by said rod when moved in one direction, to re-set said mechanism to adapt it to be operated to move the rod in the opposite direction.

5. The combination with two sections of a track, a second track which diverges from said track, and a switch movable into position to connect the rails of one of said track sections either with the rails of the other track section or with the rails of the other track, of a rod extending lengthwise of said tracks and operably connected, between its end, with said switch, mechanisms operatively connected respectively with opposite end portions of said rod, an actuator adapted to be carried by a moving train and adapted to so operate one of said mechanisms as to move the rod in one direction and to so operate the other of said mechanisms to move the rod in the opposite direction, said mechanisms comprising connections, operable by said rod when moved in one direction, to reset the other mechanism to adapt it to be operated to move the rod in the opposite direction.

6. The combination with two sections of a track, a second track which diverges from said track, and a switch movable into position to connect the rails of one of said track sections either with the rails of the other track section or with the rails of the other track, of a rod extending lengthwise of said tracks and operably connected, between its ends, with said switch, mechanisms operatively connected respectively with opposite end portions of said rod, an actuator adapted to be carried by a moving train and adapted to so operate either of said mechanisms as to move the rod in either direction, said rod, when so operated in one direction by one mechanism, being adapted to reset both mechanisms to permit either mechanism to be thereafter operated by said actuator to move the rod in the opposite direction.

60 In testimony of which invention, I have hereunto set my hand, at Philadelphia, Pennsylvania, on this 27th day of March, 1929.
